UNITED STATES PATENT OFFICE.

LEWIS C. SMITH, OF CHICAGO, ILLINOIS, ASSIGNOR TO JOHN C. CAMERON AND ALVA C. ROEBUCK, OF CHICAGO, ILLINOIS.

TONE-MODIFIER.

SPECIFICATION forming part of Letters Patent No. 729,230, dated May 26, 1903.

Application filed December 12, 1901. Serial No. 85,712. (No model.)

To all whom it may concern:

Be it known that I, LEWIS C. SMITH, a citizen of the United States, residing in Chicago, in the county of Cook and State of Illinois, have invented certain new and useful Improvements in Tone-Modifiers, of which the following is a specification.

This invention relates to improvements in violins and analogous stringed instruments whereby the sound of the strings is reinforced by means of a hollow resonant box or sounding body over or across which the strings are strung.

More especially, the invention relates to an improved device for augmenting, distributing, and modifying the tones of the instrument.

The object of the invention is to provide a device of the character referred to which may be readily applied to instruments without substantially reconstructing or modifying the construction of the same; to provide a device whereby unevenness of tone or deficiency of certain ones of the strings, as compared with others of the same instrument, may be corrected; to provide in a device of the character referred to a construction which enables the adjustment to be made without removing or disconnecting the parts of the device; to provide a construction which may be inserted in a violin-shell or other analogous closed body through such small openings as are present in the instrument, and, in general, to provide a simple and improved device of the character referred to.

The invention consists in the matters hereinafter described, and more particularly pointed out in the appended claims, and will be readily understood from the following description, reference being had to the accompanying drawings, in which—

Figure 1 is a top plan view of a violin equipped with a preferred embodiment of my invention, a portion of the top shell being broken away in order to expose the arrangement of the tone-modifier within the shell. Fig. 2 is a view, partly in side elevation and partly in longitudinally-vertical section, taken through the median line of the instrument and showing the tone-modifier in side elevation. Fig. 3 is a vertical

sectional view through the tone-modifier, taken on line 3 3 of Fig. 1.

I have discovered that by applying a support to the interior of the sound box or shell of a stringed instrument—as, for example, to the front or top member of a violin which receives the vibration of the strings from the bridge—and rigidly supporting upon this support a plurality of hollow tube-like members arranged to project freely within the sounding-space of the instrument the tone of the latter may be very greatly modified and improved, and, further, that by varying the lengths of these tubular members and their position within the instrument the sounding qualities of the several strings may be modified so as not only to improve the tone of the instrument as a whole, but also to render the strings more uniform in their sounding qualities.

According to my present knowledge, in the case of a violin the sounding-post, or rather a modified form of sounding-post, constitutes the best form of support upon which to mount these sound modifying and distributing tubular members, and I have further discovered that the sounding-post, in order to secure the best results, should also be made hollow. The sounding-post forms a peculiarly-suitable support for said tone-modifying members because of the fact that it is capable of being moved around or adjusted within the instrument to that exact position wherein it produces the best results, because it may be inserted and removed through the "f" openings and without dismembering the instrument, and, further, because when in position it is in direct bearing with both the top and bottom shell members of the sounding-body, and therefore partakes intimately of the vibration of said body. It is understood, however, in this connection, that my improved attachment might be made entirely independent of or in addition to the sounding-post of the instrument, and, indeed, in the case of such instruments as are not provided with the equivalent of a sounding-post it would of course take the form of a specially-constructed support. I may also state in this connection that I do not fully understand the

scientific theory upon which my improvement is based, but believe much of its potency to reside in the fact that the hollow or tubular members of the device impart to the 5 bodies of air contained therein vibrations which augment and coöperate with the vibrations of the larger body of air contained within the body of the instrument. I am constrained to this theory by reason of the 10 fact that although a sounding-post equipped with prongs or fingers which are not hollow, but are arranged in somewhat the same manner as are the hollow elements of my present invention, has a certain degree of efficiency 15 in modifying the tone of the instrument, yet it falls far short of securing the same results as are obtained by the present device.

Referring to the drawings, 1 designates as a whole the resonance box or body of an ordinary violin, comprising front and back 20 walls 2 3, respectively, and surrounding side walls 4.

5 designates the neck, connected with the body in the usual manner, and 6, as a whole, 25 the usual set of strings, strung across the body in the customary manner and supported in such manner as to impart their vibrations to the body through the usual bridge 7.

8 designates as a whole my improved attachment or tone-modifier, which in its preferred form and as shown in the present instance combines both the functions of the ordinary sounding-post of the instrument and of a tone-modifier possessing the peculiar 30 characteristics hereinbefore referred to. In its said preferred form the main support 9, corresponding to the ordinary sounding-post, consists of a tubular post made cylindric throughout the greater part of its length, as 35 indicated at 10, and provided at the lower end of said cylindric portion with an annular shoulder 11.

Upon the post 9 are mounted two hollow secondary supports 12 and 13, respectively, 40 each in turn being provided with a plurality of hollow tubular fingers, as 14 and 15, which are so seated within their respective supports that their hollow interiors communicate with the hollow interiors of the secondary supports.

50 As a preferred construction, I make said secondary supports in the form of hollow bar-like bodies, each provided at a point intermediate of its length with a lateral enlargement or projection 16, which is apertured to fit snugly 55 upon the cylindric portion 10 of the main support or sounding-post. These bar-like secondary supports are open at each end, as indicated at 17 and 18, respectively, and the several tubular fingers are rigidly connected 60 therewith by having their ends fitted within lateral openings 19, formed in the sides of the secondary supports remote from the sounding-post, said lateral openings or sockets being preferably arranged in divergent relation, so 65 that the hollow tubular fingers of each secondary support spread out fan fashion, as in-

dicated clearly in Fig. 1. The sockets within which said tubular fingers are seated extend through the side walls of the secondary supports, so that the interior of each finger communicates with the interior of the secondary 70 supports.

In order to further enhance the coöperative effect of the tubular members and secondary supports with the tubular post, I provide in 75 the latter, at the points encircled by the respective secondary supports, series of apertures 20, which afford communication between the interior of the tubular post and the interiors of the secondary supports. I preferably 80 provide several of these apertures, as indicated in the drawings, so that at whatever angle the secondary support may be adjusted relatively to the post one or more of said openings will afford communication between 85 said parts. In this connection it is to be understood that the secondary supports are fitted upon the tubular post with sufficient snugness to be held securely in position and in whatever angular adjustment they may be 90 placed by frictional engagement alone.

It may be further explained that in practice I have found a hard resilient or vibratory wood, such as hard maple or spruce, to be the best material from which to form the device, 95 including both the tubular post and the hollow tubular member supported thereon. I have further ascertained that the best results are secured when the walls of said tubular members are made relatively thin and of approximately uniform thickness throughout, 100 such a construction conducing to the free and uniform vibration of the several members.

The operation of the device is probably entirely obvious from the foregoing description, but it may be explained that in use the sounding-post will be arranged in approximately its normal position—namely, slightly in rear of the bridge and in the vicinity of the vertical plane of the "d" string, while the 105 two sets of tubular fingers will be arranged to extend, respectively, in the general direction of the opposite side walls of the instrument. Preferably those fingers extending toward the base side of the instrument will 110 be somewhat longer and arranged to extend in an inclined direction between the "f" and the tailpiece, while the opposite set of fingers will be preferably arranged approximately in 115 diametrically opposite direction, as shown 120 clearly in Fig. 1. However, it will be found that by varying the angular positions of the vibratory members, both with relation to each other and with relation to the strings 125 of the instrument the effect upon the sound of the instrument will be modified as well as improved. I therefore adjust these tone-modifiers in various positions until I ascertain by experiment that position best suited for the particular instrument in hand.

The present invention is not to be confounded with prior attempts in which it has

been proposed to modify the tones of a stringed instrument by applying to the interior of its sound-body some sort of a metallic vibratory device—such as, for example, a 5 tuning fork or a metallic wire gong. Such devices, while serving to modify the tone of the instrument to which they are applied, operate to very substantially change the character of the tones, while my present invention 10 has no such effect. It increases the volume of the tone of a violin, renders the violin more responsive to the bow, makes the tone of the instrument louder and of greater carrying power, particularly as to the heavier 15 strings, but does not in anywise alter the peculiar characteristic tone of the instrument which distinguishes it from other instruments, the tone remaining a pure violin tone and being modified only as to its volume, 20 sweetness, and uniformity, but not in such a manner as to make it sound otherwise than as a violin.

While I have herein shown and described what I deem to be a preferred embodiment 25 of my invention, yet it will be obvious that the details thereof may be modified without departing from the spirit of the invention, and I do not, therefore, wish to be limited to these details, except as to such claims wherein 30 they are specifically set forth.

I claim as my invention—

1. As a new article of manufacture, a tone-modifier for stringed instruments, comprising a post-like support having oppositely-extending 35 engaging ends, and one or more hollow vibratory members fixed upon said support between its ends to receive and partake of the vibration of the support, said hollow members being arranged to project freely 40 therefrom so as to extend freely within the body of the instrument when the modifier is in operative position.

2. As a new article of manufacture, a tone-modifier for stringed instruments, comprising 45 a hollow post-like support having oppositely-extending engaging ends, and a plurality of hollow vibratory open-ended fingers fixedly connected with said support so as to receive and partake of the vibration of the latter, 50 said fingers being arranged to extend divergently from said post at points between the ends thereof.

3. As a new article of manufacture, a tone-modifier for stringed instruments, comprising 55 a post-like support constructed to fit with its ends in bearing with the opposite sides of the interior surface of the resonance body of the instrument, a hollow secondary support mounted upon said post-like support and a

plurality of hollow vibratory fingers connected with said secondary support. 60

4. As a new article of manufacture, a tone-modifier for stringed instruments, comprising a post-like support constructed to fit with its end in bearing with the interior surface of the 65 resonance body of the instrument, a plurality of hollow secondary supports mounted upon said post-like support and a group of hollow open-ended vibratory fingers connected with each secondary support, said secondary supports being adjustably mounted upon said post-like support, for the purpose set forth. 70

5. In combination with a violin, a tubular sounding-post interposed between front and back walls of the violin-body, a hollow secondary support mounted upon said sounding-post one or more communicating passages 75 between the interiors of said secondary support and the sounding-post, and a plurality of vibratory fingers mounted upon said secondary support and extending freely therefrom, the interiors of said hollow fingers communicating with the interior of the secondary support and their outer ends being open, for the purpose set forth. 80

6. In combination with a violin, a tubular sounding-post interposed between front and back walls of the violin-body, a hollow secondary support mounted upon said sounding-post, one or more communicating passages 85 between the interiors of said secondary support and the sounding-post, and a plurality of vibratory fingers mounted upon said secondary support and extending freely therefrom, the interiors of said hollow fingers 90 communicating with the interior of the secondary support and their outer ends being open, for the purpose set forth. 95

7. As a new article of manufacture, a tone-modifier for violins comprising a post having 100 opposite support-engaging portions of restricted area constructed to rest in bearing with the front and back sides respectively of the body of a stringed instrument and a plurality of hollow vibratory open-ended fingers 105 connected with said support and arranged to extend divergently therefrom.

8. As a new article of manufacture, a tone-modifier for violins and analogous stringed instruments, comprising a hollow tubular 110 post of relatively small diameter, and a plurality of hollow vibratory open-ended fingers fixedly mounted directly upon said support and extending divergently therefrom.
